DESIGN FOR A NECKTIE OR SIMILAR ARTICLE

Samuel Glaser, New York, N. Y.

Application April 10, 1940, Serial No. 91,585

Term of patent 7 years

To all whom it may concern:

Be it known that I, Samuel Glaser, a subject of the King of Rumania, residing at New York, in the county of Bronx and State of New York, have invented a new, original, and ornamental Design for a Necktie, or Similar Article, of which the following is a specification, reference being had to the accompanying drawing, forming a part thereof.

Fig. 1 is a rear perspective view of a necktie embodying my new design;

Fig. 2 is a front perspective view, on a smaller scale, of the necktie shown in Fig. 1;

Fig. 3 is a fragmentary view, on a larger scale, of the back of the front part of the tie, with parts of the folded portions displaced for the purpose of exposing a part of the lining of the tie.

The dominant features of my design reside in the extension, at the larger end of the tie, of the lining beyond the folded rear portion and the edging around the lining, substantially as shown.

I claim:

The ornamental design for a necktie or similar article, substantially as shown and described.

SAMUEL GLASER.
